Inventor:
Burton S. Jordan,
By Eugene Schaeffer,
Attest.

UNITED STATES PATENT OFFICE.

BURTON S. JORDAN, OF OTTAWA, ILLINOIS, ASSIGNOR TO J. E. PORTER COMPANY, OF OTTAWA, ILLINOIS, A CORPORATION OF ILLINOIS.

DOOR-HANGER.

1,384,763.

Specification of Letters Patent. Patented July 19, 1921.

Application filed July 28, 1919. Serial No. 313,784.

To all whom it may concern:

Be it known that I, BURTON S. JORDAN, a citizen of the United States, residing at Ottawa, in the county of La Salle and State of Illinois, have invented new and useful Improvements in Door-Hangers, of which the following is a specification.

This invention relates to door hangers for folding doors, the sections of which are hinged together with one of the door sections hinged at one side of the door opening.

Among the objects of my invention is to provide a door hanger using a straight track mounted parallel to the door opening and permitting the doors to be folded one against the other and stand at an angle to the track when in fully open position. A further object of my invention is to provide such a connection between one of the doors and the hanger that the doors will be prevented from movement beyond their fully open position and from being injured or damaged by being forced or moved against the side wall of the building or the front wall thereof to which the doors are connected. A still further object of my invention is to provide a bracket and arm which may be used with either right or left-hand opening doors, and thus make the equipment a universal one. A further object of my invention is to provide a simple construction comprising a minimum number of parts, inexpensive to manufacture and to handle and install, and yet efficiently serving the purpose for which it is intended. Other and further objects of my invention will appear from the following specification, taken in connection with the accompanying drawings, in which—

Figure 1 is a side elevational view of a set of folding doors equipped with a hanger and track of my invention, the doors being shown closed;

Fig. 2 is a top plan view of the parts shown in Fig. 1, with the doors shown in full lines partially opened and in dotted lines fully opened, said figure being taken on line 2—2 of Fig. 1;

Fig. 3 is an enlarged side elevational view of the hanger and parts used for connecting the same with one of the folding doors;

Figs. 4 and 5 are vertical sectional views taken on lines 4—4 and 5—5, respectively, of Fig. 3; and

Fig. 6 is a perspective view of the bracket and arm used with the hanger and showing

such parts disconnected so as to indicate how the same may be used for right as well as left-hand opening doors.

In the drawings, I have shown a garage or other building 1, having a front wall 2 provided with an enlarged doorway 3 and side walls 4, 4, the building of course having a rear wall, roof, and floor. On the inside of the building and above the doorway 3 is a straight track or rail 5 secured to the front wall 2 by brackets 6, of any desired type and number and positioned along the length of the track at such intervals as necessary. As shown, the track 5 is in the form of a flat bar arranged on edge and secured to said wall 2, parallel to the door opening 3. The track 5 is straight throughout all portions of its length and is not curved from the building wall at either of its ends as in some equipments heretofore used. For the doorway 3 is provided a plurality of doors 7, 8, and 9, three in number in the particular equipment shown but a greater number of doors may be used if desired without departing from the spirit and scope of my invention. The door 7 is connected by hinges 10 with the inside of the front wall 2 at one side of the door opening, while the door 9 is connected by hinges 11 with the inside of the same wall at the opposite side of the door opening, as shown in Figs. 1 and 2. The door 8 is interposed between the doors 7 and 9 and is connected with the opposed edge of the latter by hinges 12, located on the outside of said doors to permit the doors 8 and 9 to fold back against each other and to one side of the door opening, as shown in dotted lines in Fig. 2. In the particular equipment illustrated, the doors 7 and 8 when closed may be connected together at their meeting or abutting edges by a pivoted latch member 13 engaging a keeper 14 on the door 8. Said latch member may be raised to disengage it from the keeper by a pivoted thumb piece 15 on the door 7.

The hanger for the folding doors 8 and 9 comprises a roller carriage 16 having a pair of rollers 17, 17 of the grooved type and traveling on the upper edge of the track 5. Said rollers are at the ends of the carriage, and depending from the same between the rollers is a carrier 18 having its lower end bent inwardly toward the building wall and extending beneath the lower edge of the track 5, as clearly shown in Fig. 4. Of the

two folding doors 8 and 9, the former is the innermost one and has secured to its upper free edge a bracket 19. Said bracket 19 is provided with elongated slots 20 vertically arranged and through which extend bolts 21 for connecting the bracket with the door, the slots permitting vertical adjustment of the bracket to facilitate its attachment to the carrier 18. The bolts 21 extend through the door 8, as shown in Fig. 5, and also through a plate 22 on the outside of the door and against which plate the heads of the bolts bear. The bolt holes in the plate 22 are preferably made square to receive like portions on the shanks of the bolts to hold the same from turning when the clamp nuts 23 are applied on the threaded ends of the bolts. The upper end 24 of the bracket 19 is arranged at right-angles to the body of the same and extends inward from the inner face of the door 8, as shown, and to which is permanently secured, by fastening members 25, an arm 26. Said arm 26 is connected at its other end by a pivot pin 27 with the lower end of the carrier 18, as shown in Figs. 3 and 4. The arm 26 is offset downward at its end connected with the bracket 19 to permit the track 5 to be spaced the required distance above the upper edge of the doorway, so that a track and brackets 6, of required size and strength may be used and not extend over the doorway to hinder the opening and closing of the doors. Moreover, the upper end 24 of the bracket 19 extends inward from the door 8 to allow the door to close in the opening 3.

When the doors are closed, they occupy the positions shown in Fig. 1, and it will be noted that the roller carriage 16 stands adjacent one end of the track 5 and beyond the door 8, to which it is connected. At such time the arm 26 is in a position parallel with the door opening 3 and at right-angles to the carrier 18. To open the doors, the latch 13 is raised and the door 7 released from the folding doors 8 and 9. The latches 28 of the doors 8 and 9 are then released by pulling on the chains attached thereto and said doors 8 and 9 break and swing inward on their hinges toward the side of the door opening 3 to which the outermost door 9 is hinged. As the doors 8 and 9 are swung open, the edge of the door 8, to which the bracket 19 is attached, moves in a path substantially below and parallel to the straight track 5, the roller carriage 16 traveling along the track 5 toward the side of the door opening to which the outer door 9 is hinged. The arm 26 being pivotally connected with the carrier 18 permits the arm to change its angular position readily with respect to the track and the carrier, but being rigidly connected with the innermost door 8 does not change its angular position with respect thereto. Thus the inner door 8 is permitted

to move along the track until it folds against the outer door 9, and when the doors are thus folded the upper edge of the inner door 8, to which the bracket 19 is attached, stands beneath the track, and the doors are allowed to be swung about the hinges of the outer door 9 to a fully open position at approximately 45° to the straight track 5. The fact that the arm is rigidly connected with the inner door 8 prevents the doors when fully open from being swung back farther than about 45° to the track, thereby preventing the doors from being injured or broken by being slammed or forced against the front wall 2 or the side wall 4. From this it follows that the side wall toward which the doors open need not be spaced far enough from the doorway 3 to allow the doors to be folded back against the front wall 2, but need only be spaced a sufficient distance from the door opening to guard against the doors striking the wall when the doors are swung into fully open position. When the doors 8 and 9 are folded against each other, further pivotal movement of the doors to fully open position is about the hinges 11 of the outer door 9, and, as said point of movement is offset from the pivotal connection of the arm 26 with the roller carriage, the latter does not travel beyond the inner edge of the inner door 8 and thus does not run off the end of the track. From this it follows that no stop member on the track is needed to prevent the roller carriage from running off the track. By having the lower end of the carrier 18 extending beneath the track 5 and the arm 26 pivoted thereto, the rollers 17, are prevented from tilting and binding against the track when traveling thereon.

As shown in the drawings, the arm 26 is connected with the upper end 24 of the bracket 19 by two fastening members 25, 25, instead of one, so as to prevent the arm from having any pivotal movement with respect to the bracket. In order that the bracket and arm may be used for either right-hand or left-hand opening doors, the bolt holes 29, and 30 in the arm and bracket are so arranged that the arm may be connected with the bracket so as to extend on either side thereof, as shown in Fig. 6, the full lines showing the arm in position to be secured to the bracket for right-hand opening doors as illustrated in the preceding figures of the drawings, and the dotted lines showing the arm in position to be connected with the bracket for left-hand opening doors. This makes a universal equipment and avoids the necessity of making a right and left-hand part or two separate types of equipment. To further prevent pivotal movement of the arm 26 with respect to the bracket 19 and, in addition, insure the arm 26 extending from the bracket at the proper angle when secured thereto, whether for right or left-hand open-

ing doors, the bolt holes 29, and 30 are square and receive a squared part 31 on the shank of the fastening member 25, as shown in Fig. 6.

The hanger construction as shown and described is particularly applicable for garage doors or any other equipment where folding doors are employed. In the drawings, I have shown the door 7 which may be opened and closed independently of the folding doors 8 and 9, this being the usual practice in building garages, although such door could be omitted and the door opening closed by folding doors alone.

While I have shown and described herein in detail one preferred form of door hanger embodying the features of my invention, yet the details of construction and arrangement of parts shown may be variously changed and modified without departing 20 from the spirit and scope of my invention.

I claim as my invention:

1. In a door structure, the combination of a straight track rigidly mounted parallel to and above the door opening, a plurality 25 of doors hinged together, there being an inner door and an outer door and the latter hinged to a stationary support at one side of the door opening, a roller carriage mounted to travel on said track, a carrier secured to 30 said roller carriage and extending downward therefrom, a bracket secured to said inner door, and a horizontal arm arranged at right-angles to said bracket and extending between the same and said carrier, said 35 arm having pivotal connection with said carrier and rigid, non-rotative connection with said bracket.

2. In a door structure, the combination of a straight track rigidly mounted parallel 40 to and above the door opening, a plurality of doors hinged together, there being an inner door and an outer door and the latter hinged to a stationary support at one side of the door opening, a roller carriage mounted 45 to travel on said track, a carrier secured to said roller carriage and extending downward therefrom and having its lower end extending beneath said track, a bracket secured to 50 said inner door and having a horizontal flange extending inward therefrom,

and a horizontal arm arranged at right-angles to said flange and extending between the same and said carrier, said arm having pivotal connection with the lower end of said carrier and rigid, non-rotative connection with the flange of said bracket. 55

3. In a door structure, the combination of a straight track rigidly mounted parallel to and above the door opening, a plurality of doors hinged together, there being an inner door and an outer door and the latter hinged to a stationary support at one side of the door opening, a hanger mounted to travel on said track, a carrier secured to said roller carriage, extending downward therefrom, and having its lower end extending beneath said track, a bracket secured to the inner door, a horizontal arm arranged at right-angles to said bracket and extending between the same and said carrier, said arm 65 having pivotal connection with the lower end of said carrier, and means rigidly connecting said arm with said bracket in a manner permitting said arm to extend from either side of said bracket for either a right- 70 hand or left-hand opening set of doors. 75

4. In a door structure, the combination of a straight track rigidly mounted parallel to and above the door opening, a plurality of doors hinged together, there being an inner door and an outer door and the latter hinged to a stationary support at one side of the door opening, a roller carriage mounted to travel on said track, a carrier secured to said roller carriage and extending downward therefrom and having its lower end extending beneath said track, a bracket secured to 80 said inner door, and a horizontal arm arranged at right-angles to said bracket and extending between the same and said carrier, 85 said arm having pivotal connection with said carrier beneath said track and rigid, non-rotative connection with said bracket; the outer end of said arm being offset downward toward said inner door. 90 95

In testimony that I claim the foregoing as my invention, I affix my signature this 25th day of July, A. D. 1919.

BURTON S. JORDAN.
